ABSTRACT

A mimeograph type of duplicating machine is made capable of printing stencils of various sizes by the use of specially constructed overlay or cover members, each of which effectively bars the passage of ink over all areas of an ink reservoir drum larger than the stencil being printed. The overlay member is made of a generally porous cloth with a rubber coating vulcanized to the cloth over all portions thereof except the portion to be covered by a stencil.

COVERING FOR PERFORATED INKING DRUMS OF STENCIL PRINTING MACHINES

REFERENCE TO PRIOR APPLICATION

This application is a continuation of application Ser. No. 224,848, filed Feb. 9, 1972 and now abandoned.

BACKGROUND OF THE INVENTION

1. Field of the Invention

Mimeograph type stencil duplicating machines generally employ a rotating drum. A major part of the cylindrical surface of the drum is provided with closely spaced apart apertures through which ink supplied to the interior reservoir of the drum may be expelled radially outwardly in the printing operation. A precut stencil is wrapped around the drum and held thereto with clamping means usually provided in areas of the drum having no apertures. As the ink moves outwardly it effectively inks the indicia material cut in the stencil and causes a transfer to and a printing of the stencil cut indicia on paper pressed thereagainst. Further, a cloth or fabric is usually interposed between the drum and the stencil as a cushion for the stencil and to gain more uniform ink distribution. This insures that the stencil will be inked over its full surface and not just at the point of contact with each aperture.

The first such mimeograph type stencil duplicating machines were made to accommodate the width of a letter or legal size sheet of paper and the length of the longer legal sheet. Since then machines of this type have been specially made to take stencils of post card size and of various marking stencil sizes. As a rule though for each size stencil desired to be printed a correspondingly sized machine has been made. Shielding or blocking portions of an apertured drum in prior devices to print a smaller stencil has been extremely difficult and rather impractical at least insofar as width is concerned.

2. Description of the Prior Art

A search has failed to produce any specific overlay or covering constructions similar to applicants' novel cover. The patent to Kvarnegard U.S. Pat. No. 2,604,847 describes a duplicating machine drum having means to secure a block-out sheet thereto, but such a block-out sheet is not further defined. It would appear the Kvarnegard block-out sheet would be a continuous sheet and not one with various size openings therein.

The patent to Ritzerfeld et al. U.S. Pat. No. 3,220,342 employs two separate spaced apart overlay sheets which are stated to be strategically positioned over the drum to expose more or less of the printing drum.

SUMMARY OF THE INVENTION

The present invention relates to a new and improved overlay sheet for the perforated drums of stencil duplicating machines.

It is a principal object of this invention to provide an overlay for the apertured printing drums of stencil duplicating machines which is basically a porous fabric having portions made impervious to the passage of ink by a synthetic rubber covering vulcanized thereto.

An important object of this invention is to provide a covering for the perforated ink dispensing drums of stencil duplicating machines which performs the sev-

eral functions of forming a cushioned base for the overlying stencil, dispersing the ink over surfaces not directly in alignment with the drum apertures and barring the passage of ink over other surfaces of the drum not covered by a stencil.

A further important object of this invention is to provide a covering for the perforated ink dispensing drums of stencil duplicating machines having a base porous fabric and an ink impervious coating fastened to selected portions thereof.

Another important object of this invention is to provide a covering for an ink dispensing perforated drum which comprises a fabric with a smooth side and a nap side and an ink impervious rubber coating vulcanized to selected portions of the nap side.

Another and further important object of this invention is to provide a covering as defined in the preceding object in which the smooth side of the fabric is positioned to engage the perforated drum and the uncovered nap side is to receive a stencil thereover while the rubber covered portions of the nap side prevents the discharge of ink from the drum at those portions.

Other and further important objects and advantages will become apparent from the disclosures in the following specification and accompanying drawings.

IN THE DRAWINGS

FIG. 1 is a perspective view detail of a perforated drum over which the overlay or covering of this invention is applied.

FIG. 2 is a front elevational view of the covering of this invention.

FIG. 3 is a sectional view of the covering taken on the line 3-3 of FIG. 2.

FIG. 4 is a sectional view taken on the line 4-4 of FIG. 2.

FIG. 5 is a sectional view taken transversely through a perforated drum as shown in FIG. 1 with the covering of this invention mounted thereon.

AS SHOWN IN THE DRAWINGS

The reference numeral 10 indicates generally a printing drum such as used in mimeograph type stencil duplicators. Ink from a supply within the drum is thrown centrifugally outwardly through closely spaced apart small holes or perforations 11 in the outer cylindrical surface of the drum. As will later be described a precut stencil is mounted over the perforated drum 10 to impart a printing to paper being fed therewith. The drum 10 includes an end wall 12, a drive shaft 13 about which the drum is rotated, a capped fill tube 14 in the end wall 12 for ink filling, and a rocking clamp 15 which extends across the drum to removably receive a cloth cover and an overlying stencil. The clamp 15 is primarily for the stencil but it is generally arranged to be positioned over the tops of both the cover and the stencil when they are extended around the drum.

A cover, designated generally as 16, is the basic subject matter of this invention. The cover comprises a porous cloth or fabric base 17 which is generally rectangular in shape. The porous cloth 17 may be a single layer or may comprise multiple layers. The cloth is preferably made of cotton or a composite of one or more of the same or different fibers. The cloth is sufficiently wide to span the width of the drum and is sufficiently long to make a complete covering of the apertured portion of the outer cylindrical surface of the

drum. Across the top of the cloth is a metal clip 18 which is firmly crimped over and around the cloth end to securely hold the clip to the cloth. Similarly across the bottom of the cloth is another metal clip 19 which is again crimpedly attached to the cloth. The cloth is one which preferably has a smooth surface 20 on one side and a nappy or rough surface 21 on the other side. It is the smooth side 20 of the cloth which is wrapped around and lies against the surface of the drum thus covering the apertures 11.

As stated above it is an object of this invention to permit one large size stencil duplicator to be used for the printing of many smaller size stencils. This is accomplished by the cover or overlay member 16. An ink impervious coating of a particular shape is fastened to selected portions of the cloth cover to bar the passage of ink through those portions. The coating may be any one of many materials such as rubber or synthetic rubber and hereinafter the use of the word rubber shall mean either a natural rubber or a synthetic rubber. The rubber coating 22 is preferably vulcanized or otherwise fastened to the nap side 21 of the cloth 17 over the certain selected areas thereof for the purpose of accomplishing an ink dam or bar to ink passage at those portions. In constructing the covering the rubber coating is applied to the nap side of the porous base cloth for the purpose of gaining better adherence of the rubber to the cloth. In the vulcanizing process the rubber coating is brought to sufficient heat to cause a bonding of the rubber to the nap of the porous base cloth. The heat applied is approximately 310° F. under pressure for about five minutes. The rubber coating 22 acts to define a smaller rectangular area 23 which has no ink impervious coating and which constitutes the area over which a stencil is placed for ultimate printing of the contents thereof. The size of the stencil to be printed determines the size of the rectangular uncovered area. A number of such covers may be optionally used with a single size drum to accommodate the printing of numerous size stencils.

As best shown in FIG. 5 a supply of ink 24 is shown within the reservoir of the drum 10. The cover 16 has its top end held by the ends of its metal clip 18 to the end walls of the drum. The cover extends across the drum under the spring clamp 15. Coiled extension springs 25 and 26 are attached to spaced positions on the cover's lower end metal clip 19. Spaced apart pins 27 and 28 are fixedly mounted in a cut-out portion 29 of the drum in a manner to project axially inwardly from the ends of the drum. The free ends of extension springs 25 and 26 are hooked over these spaced apart pins 27 and 28 to thus securely hold the cover 16 snugly against the drum surface over its full area. The covering 16 performs three functions, that of acting as a cushion for a stencil 30 to be placed thereover, that of covering the ink apertures and thus dispersing the ink over the full surface rather than at just the point of the apertures, and that of blocking the passage of ink at those portions beyond the outer perimeter of the stencil to be used for printing. The stencil 30 is held to the drum in its position over the covering 16 by the rockable spring clamp 15. In the drum presently used the clamp is placed slightly inwardly of the outer sur-

face of the drum so there is no projection beyond the cylindrical surface even with the covering and the stencil under the clamp. The uncoated area of the covering is generally placed close to the top thereof so that the clamp 15 may be used to hold the stencil.

The rubber coating 22 has been depicted in the drawing as having substantial thickness beyond the thickness of the fabric. This showing of thickness has been accentuated in order to clearly show all the elements. 10 However, in actual practice the rubber and fabric are welded into one piece with the rubber penetrating into and around the fabric threads on the nap side so that the overall thickness is substantially the same. FIGS. 3 and 5 show sharp offsets in thickness where the stencil 15 is to be placed whereas in fact the differential in thicknesses is very small so the stencil is permitted to lay flat thereover without being bent around corners at the position of the uncoated portion.

In the operation of a duplicator the rubber coated cloth covering 16 has its top end clip 18 held by its ends in the opposing end walls of the drum. The intermediate portion of the end clip 18 is disposed under the transverse drum clamp 15 in a manner to have the smooth side 20 of the cloth wrapped against the apertures 11 of the cylindrical drum. The bottom end clip 19 of the covering 16 is yieldably held by the springs 25 and 26 to the pins 27 and 28 respectively in a manner to have the covering taut and lying snugly against the surface of the drum. The precut stencil 30 is then inserted in the clamp 15 over a portion of the covering 16 so that the cut indicia lies over the uncoated rectangle 23 of the covering 16. As paper to be printed is pressed against the rotating drum 10 the stencil indicia is transferred to the paper by reason of the ink 24 moving outwardly through the apertures 11, through the uncoated portion of the cloth cover, and finally through the cut indicia in the stencil to reproduce the stencil matter on the paper.

Various details of construction may be changed without departing from the principles disclosed herein and we therefore do not propose limiting the patent granted hereon otherwise than as necessitated by the appended claims.

What is claimed is:

45 1. In combination an ink holding drum for a mimeograph type of stencil duplicator having a substantial portion of its cylindrical surface provided with a plurality of closely adjacent perforations constituting an ink dispensing screen, and a covering removably mounted over the entire screen portion of said drum, said covering comprising a porous base cloth, an ink impervious rubber coating covering selected portions of the outer surface of said porous base cloth to effect a damming of ink within the drum over those selected portions, 50 and the remaining portions of the porous base cloth being uncoated and constituting non-dammed portions, a stencil to be reproduced placed over the non-dammed portions of the porous base cloth, said rubber coating vulcanized to said porous base cloth, and said porous base cloth having a smooth surface on the side adjacent the drum and a nap surface on its outer side to which the rubber coating is vulcanized.
